UNITED STATES PATENT OFFICE.

AUGUST MARIOLLE AND GASTON MARIOLLE, OF OAKLAND, CALIFORNIA, AND
RAYMOND MARIOLLE, OF NEW YORK, N. Y.

SIGN-CHANGING EXHIBITOR.

Application filed November 24, 1924. Serial No. 751,944.

This invention relates to sign exhibiting devices wherein a number of signs are stored within a cabinet and automatically exhibited one after the other.

5 An object of the invention is to provide a device of this character which will be considerably simpler and less expensive in construction than the previous devices performing the same duty, primarily because of 10 the use of ordinary thin cardboard sheets which bear the signs, and because of a novel method of supporting the sheets.

The ordinary cardboard sheets have not been used for this purpose previously because of their liability to damage and the 15 use of the heavier sheets or of canvas material involves considerable additional expense. We have devised a novel type of sheet holder which permits the use of the cardboard or thin paper sheets without any 20 danger of tearing them and which permits them to be handled in a comparatively small space.

With the above noted and other objects 25 in view, the invention consists in certain novel features of construction and combinations and arrangements of parts, as will be more fully hereinafter set forth and pointed out in the claims. The invention may be 30 more fully understood from the following description in connection with the accompanying drawings, wherein—

The drawings accompanying this application 35 show the invention and its important details.

Figure 1 is an elevation of the cabinet showing what we will term the "front side", and partly broken away, tho it should be noted that in the construction shown both 40 front and back of the cabinet present the same appearance and both are provided with sign viewing panels.

Figure 2 is a horizontal cross-section of the cabinet, taken along the line 2—2 of 45 Figure 1.

Figure 3 is a vertical cross-section taken along line 3—3 of Figure 1, the sign sheets being omitted for the sake of clearness.

Figure 4 is an enlarged fragmentary portion of the device taken along line 4—4 of 50 Figure 2.

Figure 5 is an enlarged fragmentary portion of the device as shown in Figure 2 showing the track, chain and sign kicker 55 more clearly.

Figure 6 is a further enlarged detail showing the sign kicker as seen from the line 6—6 of Figure 5.

Figure 7 is an enlarged detail of the right hand end of the pack of signs as per Figure 60 2, but showing the locking and releasing latches for the signs as used to control the release of each sign on one side of the pack as another sign is placed against the opposite side of the pack by the automatic 65 mechanism.

Fig. 8 is a detailed perspective view of one unit of the sign kicker mechanism.

Fig. 9 is a perspective view of the card supporting frame.

Fig. 10 is an enlarged broken vertical sectional view through the frame.

Briefly described with a view to making the detailed description more easily understood, the invention consists of a cabinet 1 75 in which a plurality of vertically arranged signs 2 are placed, a viewing panel or opening 3 is arranged on opposite sides of the cabinet, and suitable mechanism carries the signs, which are on flexible sheets, one at 80 a time from one side of the pack of signs and deposits it on the other side, thus carrying it from one viewing panel to the other and at the same time reversing it side for side so that as a given sign again reaches 85 the first panel from which it was carried, the opposite or reverse side of the flexible sheet will be exposed to it, thus making both sides of the sign sheet available for different signs and exposing them alternately 90 to both panels.

The flexible sign sheets 2 are each supported by and between a vertically arranged pair of bars 4 at opposite vertical edges of the sheet and clamped at each of the four 95 corners to a hub 5 at the extreme ends of the bars of each pair by a screw or pin 6 which passes first through the end of one of the bars 4 and then through the end of a flexible strip 7 of metal which overlies the 100 flexible sign sheet 2 along the upper and lower horizontal margins, then through the second bar 4 on the other side of the sign sheet and then through the second flexible strip 7 lying parallel to the first strip, and 105 then into the hub 5 secured to the last vertical bar. The flexible strips permit the sign and frame to bend in one direction while the two vertical double bars 4 clamped to and at the side edges of the sign sheet 110

- hold the flexible sign straight in a vertical direction and the hubs 5 have projecting ends 8 extending between two tracks 9 arranged in duplicate at both ends of the bars 5 for guiding the bars and sign sheets from one side of the pack of signs to the other, while the hub portion 5 of the bars is adapted to ride on the upper edges of the lower track as a support for the traveling signs.
- 10 Vertically arranged along the vertical edges of the signs at one side of the cabinet is a cylinder 10 revolvably supported on a shaft 11 and which shaft also carries sprockets 12 one above and one below the top and bottom respectively of the signs, and within the channel formed by the double tracks are endless chains 13 passing around the sprockets so as to be simultaneously set in motion upon revolving the shaft.
- 15 The shaft passes through a false floor 14 in the cabinet and carries a worm wheel 15 driven by a worm 16 on a shaft 17 transversely arranged in the cabinet below the floor and provided with a drive pulley 18 belted at 19 to a motor 20 also below the floor and which serves as the power drive for the mechanism as well as to drive a phonograph 21 through means of another belt 22.
- 20 This phonograph has its horn 23 projecting through the side wall of the cabinet and while it has no direct bearing on the invention, is illustrative of the use of the driving motor 20 and extra under floor space for an announcing device for the signs displayed or qualities of the merchandise advertised, tho it may be mentioned that the phonograph may represent a radio or other noise maker calculated to attract people to view the changing signs.
- 25 The changing of the signs from one side of the pack to the other is effected by a finger 24 on each chain which as they simultaneously travel around the tracks in the direction of the arrow engage respectively the upper and lower extending ends 8 of the rods 2 and drag a sign from the back side of the pack around the cylinder to the front side of the pack and when registered over the front side of the pack the fingers on the driving chains pass out of engagement with the bar extensions by being deflected through the chains passing over idler sprockets 25, 26, and the sign thus released is pushed into the pack by a "kicker" to be later described.
- 30 Upon being thus pushed into the stack, the signs are all moved toward the back side of the cabinet and the rearmost one is pushed out into the line of travel of the rear run of chains so that the oncoming finger will, upon reaching the right hand edge of the sign (as seen in Figure 2), engage the ends of its bar and carry or drag it from its position at the rear viewing panel over the cylinder 10 to the front viewing panel in the manner described.
- 35 To insure that the finger 24 will not engage the first or left hand bar on the rear sign, the chain is guided by idlers 27, 28 so as to enter the rear run of tracks at an angle to escape or clear the left bar as shown in Figure 2.
- 40 Thus it will be seen that if but one finger is provided on each chain, a sign will be deposited in front of the cabinet and will be exposed to view until the same fingers pick up the rear sign and carry it over the cylinder.
- 45 To push the deposited sign squarely into the pack, the kicker is arranged to simultaneously push the four ends of the vertical bars and while this device may assume a variety of forms to effect the desired result, we here show it as comprising two horizontal shafts 29 one at the top and one at the bottom of the signs. The shafts 29 are journaled in bearings in the outer end portions of posts 44, one of which is shown in Figure 8. The posts for the upper and lower shafts 40 are respectively secured to the top of cabinet 1 and the false floor 14. Lugs with projecting pins 30 are rigidly secured at the opposite end portions of the shafts 29 and engage levers 43 pivoted to brackets 45 carried by posts 44 and disposed adjacent to the tops of the tracks 9 and adapted upon being moved by the shafts to strike the bars to push the sign into the pack. The levers are urged in a direction away from the pack 100 by a spring 31 secured to a crank arm 32 on the shaft, and another arm 33 is provided on the shafts projecting into the path of travel of the chain finger 24 so that shortly after the chain finger has disengaged the deposited sign, it lifts the arm 33 in passing and thus revolves the shaft and throws the free ends of the levers 30 against the bars to push the sign as described.
- 50 As soon as the chain finger in traveling 110 clears the arm 33 the spring 31 pulls the shaft in the reverse direction and thereby the levers out of the way to clear the track for the next sign.
- 55 As each deposited sign is pushed into the pack the sign on the opposite side is released and pushed into the path of travel of the chain as described and to insure a proper action and hold the signs vertical, a latch arrangement as shown in Figure 7 is 120 provided above and below the signs to operate on the bars or extensions as indicated.
- 60 This latch comprises two portions 34, 35 pivoted respectively at 36, 37 and coacting through means of a tooth 38 on one lever 125 engaging a notch in the other whereby when the bar 2' of the deposited sign is pushed into the pack, the hooked end of the lever 35 is raised to receive the bar and simultaneously the hooked end of lever 34 is raised to 130

release the bar 2" so that the rear sign will be ejected into the path of travel of the chain finger as described.

The signs are conveniently illuminated 5 from electric globes 39 concealed beneath a cowl 40 above each panel.

To insert or remove the signs, a door 41 is provided at the front and back of the cabinet preferably hinged as indicated at 42. 10 Having thus described our invention, it will be seen to transfer the signs horizontally from one side of the pack to the other but it will be apparent that the device may be turned on the edge so that the signs will 15 travel vertically if desired.

It should be noted that although we show a special flexible frame in which each sign is clamped, it is possible to modify this construction considerably, or, in the case of 20 signs made on thin sheet material, to dispense with all or most of it, therefore, when in our claims we say "flexible sign sheets", it is intended to include any such supporting structure as may be necessary to sustain 25 the sheet and adapt it for transporting from one position to the other as described.

We claim:

1. A frame device for a flexible generally rectangular sign sheet including rigid framing bars connected to two opposite side edges 30 of the sheet and clamping said sheet edges between them, and flexible framing bars connected to the other two side edges of the sheet and clamping said edges between them.
2. A frame device for a flexible generally rectangular sign sheet including rigid framing bars connected to two opposite side edges of the sheet and clamping said sheet edges between them, and flexible framing bars connected to the other two side edges of the sheet and clamping said edges between them, 35 said flexible framing bars being connected at their ends to the ends of the rigid frame bars.
3. A frame device for a flexible generally rectangular sign sheet including rigid fram- 40

ing bars connected to two opposite side edges of the sheet and clamping said sheet edges between them, and flexible framing bars connected to the other two side edges of the sheet and clamping said edges between them, hubs at the ends of the rigid framing bars including extensions adapted to enter tracks to guide the movement of the frame. 50

4. A framing device for a flexible display card including pairs of rigid frame members between which two opposite edges of the card are clamped, and pairs of flexible frame members between which the other two opposite side edges of the card are clamped. 55

5. A framing device for a flexible display card including pairs of rigid frame members between which two opposite edges of the card are clamped, and pairs of flexible frame 60 members between which the other two opposite side edges of the card are clamped, and securing devices connecting the ends of the pairs of flexible frame bars to the ends of the pairs of rigid frame bars and passed 65 through the corners of the card.

6. A frame for flexible display cards of rectangular shape including four pairs of framing bars, two opposite pairs of framing bars being rigid and the other two pairs 70 being flexible. 75

7. A frame for flexible display cards of rectangular shape including four pairs of framing bars, two opposite pairs of framing bars being rigid and the other two pairs 80 being flexible, and a hub secured to the ends of the pairs of rigid frame bars by connecting devices which also secure the rigid and flexible frame bars together. 85

8. A frame for a flexible sign sheet including a pair of rigid posts and pairs of flexible devices connecting the ends of the posts and adapted to clamp the edges of a display card between them.
